I. J. PLAMONDON

BOOK HOLDER

Filed June 10, 1922.

UNITED STATES PATENT OFFICE.

ISIDORE J. PLAMONDON, OF DUBUQUE, IOWA.

BOOK HOLDER.

Application filed June 10, 1922. Serial No. 567,240.

To all whom it may concern:

Be it known that I, ISIDORE J. PLAMONDON, a citizen of the United States, residing at Dubuque, in the county of Dubuque and 5 State of Iowa, have invented certain new and useful Improvements in Book Holders, of which the following is a specification, reference being had to the accompanying drawings.

10 Difficulty arises in supporting books either on display or for reading purposes, particularly where it is desired to support various kinds of books. For instance it might be desired to support certain books on a greater 15 incline than others, when on display, and it may be desired to support other books for reading purposes on different angles. Devices heretofore used for this purpose are more or less complicated, and where they are 20 comparatively simple, they do not permit of various adjustments.

It is therefore, the purpose of the present invention to provide a book holder or support, which is very simple in construction, 25 and which involves improved features, whereby books may be supported upon various inclined positions.

Another purpose is to provide a support or holder consisting of a base, a support operatively mounted on the base, with means 30 hingedly carried by the support and adapted for adjustment to different positions intermediate the support and the base, whereby the support may be held in different inclined 35 positions, for the purpose of supporting a book, there being means at the lower portion of the support, to prevent displacement of the book. The book may be held in a closed position, on display, or in an open position 40 for reading purposes, copying, posting, etc.

Still another purpose is to provide a support or holder for books including side leaves or supports, for the purpose of supporting the back portions of the book in different 45 positions, there being means, such as triangles or supports or braces carried by the leaves of the book support or holder, to hold said side leaves or supports in such different angular positions. In fact the tri-

50 angles or braces between the supports for the back portions of the book, and the main inclined support are similar to the triangle or brace, which is carried by the main book support, the one difference being in size.

55 In Patents Nos. 1,197,233 and 1,228,595, issued to Isidore J. Plamondon and Robert

Short, and Isidore J. Plamondon, respectively on September 5, 1916 and June 5, 1917, sliding blocks triangular in shape are used 60 for holding the main book support in different inclined positions, and also for holding the side leaves of the book support in different inclined positions. The present invention, as a further purpose aims to eliminate the sliding triangular blocks or braces 65 of these prior patents, and in lieu thereof provide triangles or braces, pivotally supported upon the main book support and the side leaves, for the purpose of holding such parts upon different inclined positions, 70 thereby obviating the necessity of manually moving the braces, so as to hold the main book support and the side leaves as may be desired. The present invention is a decided 75 improvement over the structure in the former book holder Patent No. 1,197,233, in that the construction and arrangement of the parts are simpler, more practical, and much easier to manufacture, and will at the same time enable the various parts to perform their 80 purposes much easier and quicker.

The book holder will also give a greater degree angle than can be obtained by the 85 sliding blocks in the Patent No. 1,197,233, which may be required for certain uses, and at the same time will give all the angles required for ordinary uses.

The present construction of book holder or support may be constructed of any suitable 90 material, either wood, metal, or any other suitable materials or composition of materials, it depending upon the services to be rendered, and may be cheaply made, and sold at a reasonable profit.

It is to be understood that the particulars herein given are in no way limitative 95 and that while still keeping within the scope of the invention, any desired modifications of detail and desired proportions may be made in the apparatus according to circumstances.

The invention comprises further features and combination of parts, as will be herein-after set forth, shown in the drawings and claimed.

In the drawings:—

Figure 1 is a perspective view of the improved book support or holder, viewing the same from the rear;

Figure 2 is a similar view, showing the 110 main support for the book adjusted to assume an entirely different angle;

Figure 3 is a perspective view of the book holder, showing the main book support adjusted to assume another angle, and the side leaves or supports and the back of the book 5 adjusted at different angles to those shown in Figures 1 and 2;

Figure 4 is a perspective view of the improved book holder or support, viewing the same from the front, thereby showing the 10 side leaves or supports for the back of the book, and also showing the clamping rods, leaf-holders, for not only holding the leaves of the book in place, but also hold the back portions of the book against the side leaves 15 or supports;

Figure 5 is a detail view showing the mounting of the clamping rods;

Figure 6 is a sectional view on line 6—6 of Figure 5;

Figure 7 is a detail view of a solid triangle 5^a;

Figure 8 is a detail perspective view of a U-shaped triangle 5^b;

Figure 9 is a detail view showing ears 25 8 struck-up from the support 4;

Referring to the drawings, 1 designates the base of the book holder, which may be constructed either of wood, metal or any other suitable material or composition of 30 materials, and may be made any suitable proportions. The base is provided with feet 2, which may be constructed of rubber or any other suitable material, to hold the base spaced from a stationary support on which 35 it rests.

Hingedly or otherwise connected to the base as at 3 is a main book support 4, which may be disposed in various inclined positions, and supported in such positions by 40 means of a triangle or brace 5. Fastened to the back of the main support 4 by means of rivets, screws or the like 6 is a bracket plate 7, in bearings of the ears 8 of which a suitable headed pin 9 is mounted. The 45 triangle or brace 5 is constructed of suitable metal, either cast, or sheet metal, or may be made of wood, or any other suitable material, and at one corner, the triangle or brace is provided with a sleeve 10, through 50 which the headed pin 9 engages, thereby pivotally mounting the triangle or brace upon the rear face of the main support 4.

When the book holder is made of metal or other suitable material, ears 8^a may be 55 stamped out of the main book support 4 and the side leaves 14, thereby eliminating the necessity of rivets or screws, which are utilized for holding the bracket plates 7 to the support. Obviously it is unnecessary 60 to construct the angles 5 and 16 with sleeves 10, for they can be made solid or U-shaped as shown in Figures 7 and 8. These angles are designated by the numerals 5^a and 5^b, the consequence being a triangle, regardless 65 of the manner of construction.

Obviously by tilting this triangle in any one of three different positions, the main book support 4 may be supported upon different inclinations, such as shown in Figures 1, 2 and 3.

A suitable ledge or shelf 11, constructed of sheet metal or any other suitable material is suitably secured to the lower edge 12 of the main book support 4, thereby preventing the book from movement downwardly.

Secured upon the forward face of the main book support 4 and arranged centrally thereof is a strip 13 of any suitable material, to the longitudinal edges of which the side leaves 14 of the book holder are hingedly mounted as at 15. When the strip 13 and the side leaves 14 are constructed of metal or other suitable material, the leaves 14 may be hinged in any other manner, or to a different part of the book holder, so as to serve the same purpose. The side leaves 14 are provided for the purpose of supporting the back portions of the book upon different inclinations, when the book is open, as will be clearly seen in Figures 90 1 and 4.

Pivotaly mounted on the rear faces of the side leaves 14 are additional triangles or braces 16. These triangles or braces are similar to the triangle or brace 5, and are mounted upon the side leaves in a similar manner, and may also be disposed in various positions, to hold the side leaves in different inclined positions, that is to say relatively to the main book support 4.

The adjacent faces of the lower part of the strip 13 and the main book support are chambered out to provide a cavity 17, for the reception of coil springs 18, which are constructed from a single length of spring wire, or may be made of two pieces of wire, considering the cost and convenience in the construction. Suitable book clamps or clamping rods 19 are pivotally mounted in the ledge or shelf 11, and their lower portions have right angle arms, which extend through the cavity, and upon which the coil springs are mounted. The remote ends of the coil springs are connected to the lower lateral arms of the clamping rods, so as to tension the rods for the purpose of causing their arms 21 to bear upon the leaves of the book, thereby not only holding the leaves down, but also holding the back portions of the book upon the side leaves 14 of the book holder.

It will be noted that the side leaves 14 of the book holder may be disposed in various positions, whereas the main support 4 may likewise be disposed in various positions by means of similar braces or triangles.

From the foregoing it is obvious that there has been devised a very simple, efficient and practical book holder, which can be cheaply made and sold reasonably, and which may 130

be used for supporting books on tables, or supporting books for reading purposes, preferably the latter. In fact the holder may be used in the pulpit, and serve as a 5 very useful purpose for supporting the Bible, and also for supporting heavy ledgers, cash books, journals, abstracts books, tax record books, etc. In the latter case, the book holder may be increased in 10 size.

The invention having been set forth, what is claimed is:—

1. A book holder, comprising a base, a main book support hingedly mounted upon 15 the base upon one edge thereof, and a triangular loop member having a transversely disposed hinge pin extending in a direction transversely of and mounted in bearings of the rear face of the main book support, 20 whereby the triangular member may be swung rearwardly to assume different positions on the base, to support the main book support in various inclined positions.

2. A book holder, comprising a base, a 25 main book support hingedly mounted upon the base upon one edge thereof, and a triangular member having a transversely disposed hinge pin extending in a direction transversely of and mounted in bearings of 30 the rear face of the main book support, whereby the triangular member may be swung rearwardly to assume different positions on the base, to support the main book support in various inclined positions, side 35 leaves hingedly mounted upon the front face of the main book support, and provided with means on their rear faces to cooperate

with the main book support, for holding the side leaves in different inclined positions relatively to the main book support. 40

3. A book holder, comprising a base, a main book holder hingedly mounted thereon adjacent one edge thereof, means carried by the rear face of the main book support and cooperating with the base, for holding 45 the main book support in different inclined positions, side leaves hingedly mounted upon the front face of the main book support, for the purpose of supporting the back portions of the book when in open position, 50 triangular members or braces having hinge pins extending in parallel directions with the length of the side leaves and mounted in bearings thereof, whereby said triangular members or braces may be swung laterally to the leaves to assume different positions on the main book support, to hold the leaves in various inclined positions. 55

4. A book holder, comprising a base, a book support hingedly mounted on one edge 60 of the base and provided on its rear face with a horizontal pivot, a triangular member mounted on said pivot and adapted to assume three different positions, one face and one corner of the triangle engaging the 65 rear face of the support and said base, one face of the triangle to engage the base, or the two faces which extend from the pivot of the triangle to engage the support and the base. 70

In testimony whereof I hereunto affix my signature.

ISIDORE J. PLAMONDON.
